CLAIM

The ornamental design for a plug force tester, as shown and described.

DESCRIPTION

FIG. 1 is a perspective view of an embodiment of a plug force tester, showing our new design;

FIG. 2 is a front view thereof;

FIG. 3 is a rear view thereof;

FIG. 4 is a side view thereof;

FIG. 5 is a second side view thereof;

FIG. 6 is a top view thereof;

FIG. 7 is a bottom view thereof;

FIG. 8 is a further perspective view showing additional, optional features for a design of a plug force tester;

FIG. 9 is a further front view thereof showing additional, optional features;

FIG. 10 is a further rear view thereof showing additional, optional features;

FIG. 11 is a further side view thereof showing additional, optional features;

FIG. 12 is a further second side view thereof showing additional, optional features;

FIG. 13 is a further top view thereof showing additional, optional features; and,

FIG. 14 is a further bottom view thereof showing additional, optional features.

The broken lines in the Figures are for the purpose of illustrating unclaimed portions of the plug force tester and form no part of the claimed design.

The shade lines in the Figures show contour and not surface ornamentation.
